SHEAR AND TENSION PATCH

John Kintas, Wichita, Kans., assignor to Beech Aircraft Corporation, Wichita, Kans., a corporation of Delaware

Application December 2, 1943, Serial No. 512,653

5 Claims. (Cl. 73—88)

1

The invention here disclosed relates to the testing of thin panels, such as largely employed in the construction of aircraft.

For strength testing and other purposes, it is necessary at times to apply to thin, usually hard surfaced panels of such materials as aluminum, plywood and the like, and which may be either flat or curved, loads that may be normal, parallel or skewed relative to the surface of the panel.

Under such test conditions furthermore, it is necessary that the strength of the panel be not altered by the stiffness of the load applying means and that the applied load be substantially uniformly distributed over an area of sufficient size to preclude failures of a localized nature.

The main objects of this invention are to provide satisfactory means for applying load to any flat or curved surface in directions normal, parallel or skewed relative to such surface, without deforming or altering stiffness or other characteristics and which will be readily applicable to the panel or other surface under test.

Other desirable objects and the novel features by which the purposes of the invention are attained are set forth or will appear in the course of the following specification:

The drawing accompanying and forming part of the specification illustrates certain present typical embodiments of the invention. Structure however, may be modified and changed as regards such illustration, all within the true intent and broad scope of the invention as hereinafter defined and claimed.

Fig. 1 in the drawing is a broken and part sectional view, illustrating a shear patch applied to an aircraft wing panel.

Fig. 2 is a broken plan view of the same.

Fig. 3 is a side elevation of a tension patch applied to the back of a plastic pilot seat.

Fig. 4 is an enlarged part sectional view as on line 4—4 of Fig. 3.

Fig. 5 is a further enlarged sectional detail as on line 5—5 of Fig. 4.

In Figs. 1 and 2, the specimen under test is a wing panel 7, of thin, flat, smooth, substantially impervious more or less hard surfaced material, such as aluminum, plywood or the like.

While any suitable flexible material of any shape or size may be employed, the patch is shown as comprising a pad or strip 8, of cloth, elongated in the direction of pull, conformed to and secured continuously and uniformly to the surface of the panel by an underlying layer of adhesive 9.

Traction is applied in the illustration by a pull bar 10, located in the bight 11, of the material 55 being permitted to become thoroughly dry, 30

2

folded back and secured to the patch portion by stitching 12.

The pull bar is loaded by weights 13, connected by cable 14, passing over the pulley 15, to the pull bar.

The tension patch differs from the shear patch, particularly in the method of applying the load.

As shown in Figs. 3, 4 and 5, the tension patch is made up of a layer of woven fabric 8a, secured to the specimen under test, in this case, the back panel 7a, of a plastic pilot seat, by a continuous layer of adhesive 9a, but pull of the loading cable 14a, is applied through a conically distended fabric pull disc 16, secured about its edges to the patch disc by heavy stitching 17.

Connection of the cable to the pull disc is effected by a metal ball 18, swaged on the end of the cable and seated in a conical or dimpled metal washer 19, engaged within the pull disc.

20 The two types of fittings illustrated have been found to answer for most testing purposes. The single layer of strong flexible fabric, such as heavy canvas, readily conforms to the surface under test and can be firmly attached to the test surface by a cement which will adhere to a metallic or other relatively hard surface and penetrate the woven fabric and in hardening or solidifying, form a positive, practically permanent bond between the two. This union of the patch with the test piece is accomplished without altering or impairing the surface or body characteristics of the material under test. In the first instance, Figs. 1 and 2, the shear load is applied to the aluminum skin on the nose of an airframe, uniformly, over a sufficiently extended area for test purposes, without indenting, penetrating or in any other way altering the physical character of the structure. Here the load is applied uniformly in the general direction of extent of the patch. Similarly, in the tension patch Figs. 3, 4

30 and 5, the structure is not loaded through the fitting. The fittings transmit load, in the second instance, through the fabric pull disc, to the cemented disc and the loaded surface is not deformed in any way, since the larger cloth disc, only is cemented to the structure.

While different adhesives which will meet the requirements of the invention may be employed and different modes of application used, the following is cited as one preferred example.

First the surface to which the patch is to be applied should be thoroughly cleaned. Then assuming this to be an aluminum surface, two prime coats of 62730-3 are brushed on, each coat 50 being permitted to become thoroughly dry, 30

minutes usually being sufficient drying time for each coat. Then two coats of diluted and accelerated cement composed of EC-539 with approximately 25% toluol are brushed onto the canvas and onto the wing section over the primer, the first coat in each case being allowed to become nearly dry before adding the second coat. Finally two medium brush coats of EC-539A with accelerator EC-566 in generally understood proportions and undiluted are applied over the previously applied two coats on the canvas and dried to a tack condition. The canvas, with this total of four brush coats is then applied over the two coats on the wing section and rolled or wiped down into continuous, firm engagement. The bond may be air dried for about 12 hours and then heated under infra-red lamps for about 3 hours. After removing the lamps, the entire unit should be permitted to cool before testing shear strength.

The patches may be of various sizes and shapes to meet the needs of particular tests and two or more may be used, instead of a single patch. These patches may be applied in restricted or more or less inaccessible places. The conforming of the flexible patch material to the surface with interposed adhesive and baking in that relation by infra red rays, provides a bond which will uniformly distribute and carry the full test load and without having altered the natural characteristics of the test piece. The test loads as has been seen, may be applied at any angle or in line or parallel with the absolute or approximate plane of the surface under test.

What is claimed is:

1. A loading patch for the shear testing of aircraft panels, comprising a load applying layer of thin, flat, flexible, non-stretching, strong interwoven fabric conformable by reason of its flexibility to the varying surface contours of aircraft panels or the like, adhesive capable of bonding with the surface of such panels, said adhesive incorporated in and impregnating said permeable woven fabric in its flexibly conformed condition and forming at the surface of the fabric which is opposed and conformed to the surface of the panel a continuous, coextensive, tenacious bonding layer, said woven fabric having an extended unattached portion at one edge folded back upon itself and secured in the form of a bight, a pull bar seated in said bight and means connected with said pull bar for applying a test load thereto.
2. A tension loading patch for tension loading an aircraft panel or other object, comprising a load applying layer of thin, flat, flexible, non-stretching, strong interwoven fabric conformable by reason of its flexibility to the varying surface contours of aircraft panels or other objects to be tested, adhesive capable of bonding with the surface of the object to be tested, said adhesive incorporated in and impregnating said permeable woven fabric in its flexible conformed condition and forming a continuous coextensive tenacious bonding layer at that surface of the fabric which is opposed and conformed to the surface of the object under test, a fabric pull pad secured about its rim and over a considerable portion of its area to said flexible conforming fabric and a pull connection attached to the central portion of said fabric pull pad and inside that area which is attached to the flexible conforming layer of fabric.
3. A loading patch for the strength testing of

aircraft structures comprising a load applying layer of thin, flat, flexible, non-stretching, strong interwoven fabric sufficiently pliable to be conformable to the varying surface contours of aircraft structure, said pad having incorporated therein, in its flexible, conformable state, an adhesive which can be treated to bond the pad to the surface of a part to be tested and whereby said pad may be applied directly to the surface by simply pressing the same into smoothly conformed engagement over the surface and treating the adhesive in the pad to bond the pad in its conformed state to such surface, and a load applying pull connection flexibly connected with a considerable area of said pad and thereby arranged to transmit the test load substantially uniformly to the pad and thus to distribute the load substantially uniformly over the surface to which the pad is attached irrespective of variations in contour of the surface.

4. As a new article of manufacture, a loading patch for strength testing aircraft structures comprising a substantially circular load applying pad of strong, flexible, heavy canvas, a conically distended smaller pad of heavy canvas secured over the outer face of said first pad by heavy stitching about the rim of the same, flexible adhesive medium incorporated in said load applying pad and extending in a bonding layer over the inner face of the same, said flexible bonding layer being conformable along with said flexible canvas load applying pad to varying surface curvature of aircraft structures and said adhesive being of a character which can be treated to form a bond with the surface of a structure under test and whereby the patch may be united with various surface conformations by treating said adhesive to effect bonding with said surface and pressing said pad into smoothly conformed engagement with the surface, a centrally disposed load applying washer within said conically distended pad and a pull connection engaged with said washer.

5. As a new article of manufacture, a loading patch for strength testing aircraft structures comprising a layer of strong, flexible, heavy canvas and a layer of heavy canvas secured by heavy stitching over the outer face of said first layer, flexible adhesive incorporated in said first layer and extending over the inner face of the same as a substantially continuous bonding layer, said adhesive being of a nature which can be treated to effect bonding of the surface layer with the surface of the structure to be tested and whereby said loading patch may be united with structures of varying curvature by simply treating the adhesive to effect bonding with the surface of the structure and by pressing the flexible adhesive impregnated canvas layer into continuous smoothly conformed engagement with the surface of the structure under test and load applying pull means connected with said second mentioned canvas layer.
